UNITED STATES PATENT OFFICE.

WILLIAM L. WHITTIER, OF BEVERLY, MASSACHUSETTS.

SHINGLE-STRIPPER.

1,218,145.

Specification of Letters Patent.

Patented Mar. 6, 1917.

Application filed November 7, 1913. Serial No. 799,803.

To all whom it may concern:

Be it known that I, WILLIAM L. WHITTIER, a citizen of the United States, residing at Beverly, in the county of Essex and State of 5 Massachusetts, have invented new and useful Improvements in Shingle-Strippers, of which the following is a specification.

This invention relates to improvements in shingle strippers. More particularly the 10 invention relates to tools for stripping the shingles from the roof of a house or other building. The details of the invention are set forth in the appended claims, the intention being that the patent, as expressed in 15 the claims, shall cover whatever features of novelty exist in the invention disclosed.

In the accompanying drawings:

Figure 1 is a sectional elevation of a detail embodying the invention; and 20

Fig. 2 is a plan of the same.

Referring to the drawings, it will be seen that the tool consists essentially of the blade 10 and a handle consisting of a socket piece. 11 and a wooden staff 12. The blade consists of a plate, which may preferably be of sheet metal of proper hardness and stiffness having a width, as seen in Fig. 2, sufficient to operate upon two or more shingles at once. The tool represented in the drawing, having 25 a width of about seven inches, and having a length of about eight inches is suitable for this and for the diverse leverage functions about to be described. The forward end of the blade is provided with teeth 13 and is 30 turned upward at a small but distinct angle with respect to the rest of the blade, thus dividing the blade into two portions marked respectively *a* and *b*. The angle 16 between these two is, in the specimen which is por- 35 trayed, about two and one-half inches from the forward edge of the blade; and the part *a* turns up from the plane of the part *b* at such an angle that the edge of the blade is about seven-eighths of an inch above that plane. The teeth 13 are so designed as to engage under heads of nails which may be holding the shingles in place in order to extract such nails by lifting them out of the 40 wood. The considerable extent of the blade, in width, enables a number of such nails to be engaged at once wherever they may happen to be located along the width of the blade. A similar row of serrations or teeth 45 14 is represented as being at the rear end of the blade. The handle is attached at about the middle of the *b* portion and runs up

backward, at a small angle with the plane of the *b* portion, and may be of suitable length so that the implement, being held with both hands, is used with a forward 60 swinging or thrusting movement of the workman's arms. In the drawings the angle of the handle is about 30°, and the handle is maintained at this angle by its flattened end portion 15 which is securely riveted upon the 65 *b* portion of the blade. The rear teeth 14 are turned upwardly slightly, as seen in Fig. 1.

In using the tool the workman holds it at such an angle that the leading edge 13 can be thrust under the bottom row of 70 shingles as far as the angular bend 16 between the two portions *a* and *b*. Upon de- 75 pressing the handle, with the tool in that position, the bottom corner 16 of the tool constitutes a fulcrum close to the edge, so that a powerful lifting effect is exercised. After the handle has been depressed far enough the leverage suddenly changes and the rear end 14 of the blade constitutes the 80 fulcrum. The result of this is, that in first starting the shingle, which may involve the withdrawing of some nails which are holding it, there is a powerful leverage; but after these nails have been withdrawn a distance great enough to loosen them, which involves 85 a relatively considerable downward swing of the handle 12, the leverage instantly changes so that during the latter portion of the downward swing a lifting movement of the forward edge 13 takes place, which is 90 very considerable in extent as compared with the corresponding handle movement, because the leverage has suddenly been reduced to one-third or one-fourth of what it 95 was.

The breadth of the blade results in the tool's picking up all nails within a fairly wide path; and the tool finds these automatically as it swings in the workman's arms, without his having to look for or even 100 to see them; and the combination of lever- ages is such that he can proceed rapidly along, with his body in suitable poise, without having this poise destroyed either by the exertion of strength required to extract 105 the nails or by the length of body movement involved in following the swing of the handle.

In the nature of the work to which this implement applies the workman has to drive 110 the forward edge into the rather small crack under a shingle. The swinging, thrusting,

motion with which the described tool is handled, which is made possible by the described construction, enables the workman to do this with remarkable accuracy and ease. When the outer end of the shingle has been started up in this manner, if the whole shingle does not come on the original drive the tool can be easily worked in farther until the forward edge either engages the 5 nails or is so close to them that they are worked up on the leverage from the corner 10 16; after which the whole shingle and nails may be thrown up, and the region under the entire width of the tool cleared by slight 15 further depression of the handle.

I claim as my invention:

1. A stripping tool for shingles comprising the combination of a broad plate of sheet metal having a forward edge continuously adapted to engage nail heads, and a handle extending backward from the upper side of the plate far enough to make the tool as a whole suitable for swinging by both arms of the user, said handle 20 extending at an acute angle with the plate; the under side of the plate having a forma- 25

tion adapted to serve as a fulcrum near said forward edge and another formation adapted to serve as a fulcrum relatively far from said forward edge; whereby the forward 30 swing of the tool engages it under a plurality of shingles, and depression of the handle lifts the said forward edge with a preliminary powerful and a subsequent rapidly moving leverage.

2. A stripping tool for shingles comprising the combination of a relatively broad plate of sheet metal bent at an obtuse angle near its forward edge and relatively far from its rear edge, combined with a handle 40 long enough to adapt the tool for swinging forward by both arms of the user, said handle extending backward from the top of the plate at a small angle with the plane of the rear portion thereof.

Signed by me at Beverly, Mass., this 45 twenty-ninth day of October, 1913.

WILLIAM L. WHITTIER.
